UNITED STATES PATENT OFFICE.

THOMAS COCHRAN AND JAMES COCHRAN, OF BROOKLYN, NEW YORK.

ELECTROPLATED INSULATED CONDUCTOR OF ELECTRICITY.

SPECIFICATION forming part of Letters Patent No. 236,986, dated January 25, 1881.

Application filed October 13, 1880. (No model.)

To all whom it may concern:

Be it known that we, THOMAS COCHRAN and JAMES COCHRAN, both citizens of the United States, residing at Brooklyn, in the county of 5 Kings and State of New York, have invented new and useful Improvements in Electroplated Insulated Conductors for Electricity, of which the following is a specification.

This invention consists in the combination, 10 in an electric conductor, of two primary conductors, each composed of a core of metal wire, a non-conducting envelope surrounding said core, a conducting-layer formed on the non-conducting envelope, and a second non-conducting envelope surrounding the conducting-layer, said non-conducting envelopes being 15 partially cut away to expose the end of the core and a portion of the conducting-layer in each of the two primary conductors, a connection 20 between the cores of the primary conductor, formed by twisting these cores together, a non-conducting envelope surrounding this connection of the cores, a metal wire connecting the conducting-layers of the primary 25 conductors, and a non-conducting envelope surrounding this connecting-wire and the exposed parts of the conducting-layers, so that a connection is made between the cores of the two primary conductors, and another connection 30 between the conducting-layers of said primary conductors; and said connections are protected against moisture or the influence of the atmosphere.

Our invention is illustrated in the accompanying drawings, in which Figure 1 is a perspective view of a portion of a conductor constructed according to our invention. Fig. 2 is a transverse section of same. Figs. 3, 4, and 5 illustrate the manner of connecting two of our 40 conductors.

Similar letters indicate corresponding parts.

In constructing our conductor we commence with a wire of copper or other good electrical conducting material, as shown at *c*, Fig. 1. This 45 wire *c* is incased in a sheath of india-rubber, gutta-percha, or other equivalent non-conducting material, and on this sheet is formed, by electrolysis, a conducting-layer, *e*, of copper or other conducting material, which layer may be 50 again incased in a sheath, *f*, of india-rubber or other non-conducting material, and so on.

It will be seen that the core *c* and the conducting-layers *e* *g* are exposed at their ends, the non-conducting layers *d*, *f*, and *h* being partially cut away, so that the core *c*, and also 55 the conducting-layers *e* *g*, can be conveniently connected, each to a separate battery or source of electricity, and different electric currents can be sent through our conductor without difficulty. The several layers may be produced 60 by passing the wire *c* first through a vat containing the non-conducting substance in a molten condition, then through a drying-oven, then through a vat containing the solution for electroplating, then again through a vat containing a non-conducting substance in a molten condition, and so on.

In order to make connections between two of our conductors, we proceed as follows: The copper wires *e* of the two conductors which 70 are to be connected are twisted together, as shown in Fig. 3, the insulating-layers *d* having been removed, so as to expose a sufficient length of the inner wires, *c*. After the connection is made a thin layer, *i*, of india-rubber 75 or gutta-percha, is formed to embrace and protect the exposed parts, (see Fig. 4,) and then a thin copper wire, *j*, is wound round the second conducting-layers, *e* *e*, of both conductors and round the layers *i*, the loose ends of 80 said wires being finally connected to each other. The copper wire *j* is then incased into a sheath, *k*, of india-rubber or other non-conducting substance, and a thin copper wire, *l*, is wound round the third conducting-layers, *g* 85 *g*, and round the non-conducting sheath *k*, as shown in Fig. 5, and so on, the whole being finally bound up with an insulating material.

The advantages derived from this invention 90 are as follows:

First. Any number of conductors can be readily connected to batteries or other generators of electricity, and brought into a narrow compass of space, and at the same time be perfectly insulated from each other.

Second. Our conductors are applicable for burglar-alarms, as every attempt to cut the wire would almost certainly, in breaking an intermediate non-conducting layer, force together the two conductors separated thereby, 95 and thus close a circuit between two opposite battery-poles, connected to said conductors,

respectively, and cause the operation of an electrical signal apparatus included in the said circuit.

Third. The advantages for making powerful induction-coils are obvious. In passing an electric circuit through the inner wire, *c*, a current is induced in the next conducting-layer, *e*, which, in fact, takes the place of the secondary wire of the induction-coil, and which ⁵ *braces* the primary wire *c* throughout its whole length, whereby the effect of the induction-coil is materially improved. An induction-coil thus constructed, however, forms the subject-matter of a separate application for a patent, ¹⁰ and we do not therefore give a more detailed description in this specification. ¹⁵

Fourth. The metallic or electrical coating is also available, when brought into connection with the earth, for conveying any induced currents. ²⁰

Fifth. If in Fig. 1 the outside conducting-layer *h* is left off, the metallic conducting-layer *g* will act as an effective protector for the insulating layer or layers embraced by it. ²⁵

We do not claim as our invention the production of metallic layers upon insulating-layers by electrolysis; neither do we claim, broadly, an electric conductor composed of one or more non-conducting layers and two or more ³⁰ conducting-layers formed on said non-conducting layers by electrolysis, such having already been described in the English Patent No. 277 of 1858.

What we claim as new, and desire to secure by Letters Patent, is—

35

The combination, in an electric conductor, of two primary conductors, each composed of a core, *c*, of metal wire, a non-conducting envelope, *d*, surrounding said core, a conducting layer, *e*, formed on the non-conducting envelope *d*, and a second non-conducting envelope, *f*, surrounding the conducting-layer *e*, said non-conducting envelopes *d f* being partially cut away to expose the end of the core *c* and a portion of the conducting-layer *e* in each ⁴⁰ of the two primary conductors, a connection between the cores *c c* of the primary conductors formed by twisting these cores together, a non-conducting envelope, *i*, surrounding the connection of the cores, a metal wire, *j*, connecting the conducting-layers *e e* of the primary conductors, and a non-conducting envelope, *k*, surrounding the connecting-wire *j* and the exposed parts of the conducting-layers *e e*, substantially as and for the purpose ⁴⁵ set forth.

In testimony whereof we have hereunto set our hands and seals in the presence of two subscribing witnesses.

THOMAS COCHRAN. [L. S.]
JAMES COCHRAN. [L. S.]
